UNITED STATES PATENT OFFICE.

AMOS L. FOREMAN, OF BALTIMORE, MARYLAND, ASSIGNOR TO FOREMAN'S SYSTEMS, INCORPORATED, OF WILMINGTON, DELAWARE, A CORPORATION OF DELAWARE.

BOTTLE-CRATE.

1,314,317.

Specification of Letters Patent. Patented Aug. 26, 1919.

Application filed March 10, 1917. Serial No. 153,907.

To all whom it may concern:

Be it known that I, AMOS L. FOREMAN, a citizen of the United States, residing in Baltimore, Maryland, have invented certain 5 Improvements in Bottle-Crates, of which the following is a specification.

My invention consists of a bottle crate of that type shown in my United States Letters Patent No. 1,050,823, of January 21, 1913, 10 and relates particularly to the manner in which the longitudinal partition members are attached to the ends of the crate, the object of my invention being to effect such attachment in a way that will be simpler and 15 more secure than the method formerly employed by me, and produce a crate the manufacture of which will require very little special machinery.

This object I accomplish in the manner 20 hereinafter set forth, reference being had to the accompanying drawing, in which—

Figure 1 is a longitudinal vertical section of a crate constructed in accordance with my present invention;

25 Fig. 2 is an enlarged vertical section showing the manner in which a longitudinal partition member is secured to an end of the crate;

Fig. 3 is a perspective view of a portion 30 of the inside of an end of the crate showing a recess for the reception of an end of a longitudinal partition member, and

Fig. 4 is a perspective view of an end of such a longitudinal partition member.

35 As in my previous patent the crate has opposite ends which are composed of pieces 1 and 2, opposite sides which are composed of pieces 3 and 4, and it is equipped with a laced wire bottom 9, and with longitudinal 40 partition members 11 and transverse partition members 12. In case a crate has more than one partition structure, the sides will be composed of an accordingly increased number of pieces.

45 Each longitudinal partition member 11 consists of a flat metal strip, and wherever it is necessary to attach an end of a strip to an end member of the crate a kerf 13 is formed in the inner face of such member of 50 the crate. Immediately below the kerf 13 and in communication with the bottom thereof is formed a notch 14 for the reception of the head of a nail 15, by means of which the end of the partition strip is secured in place,

Each end of each strip is provided with 55 a perforation 16 which, when such end is placed within a kerf 13, is in alinement with the notch 14, the strip projecting into the body of the end of the crate as far as the dotted line α shown in Fig. 4. The securing nail 15, the diameter of which is slightly less than the diameter of the perforation 16, is then placed in position with its point in the perforation and driven upwardly and diagonally through the perforation into the 60 end member of the crate. By means of this improved method of effecting the attachment of the partition member to the end member I am enabled to obtain a more secure attachment with the use of one nail than I 65 previously obtained with the use of two, for the reasons that, having the nail-head-receiving notch in communication with the kerf which receives the end of the strip there is 70 less weakening of the material of which the 75 end of the crate consists and the nail is gripped by the material entirely above the end of the partition and at a point where there has been no weakening of its structure whatever.

80 It is also easier to assemble a crate constructed in accordance with this invention, for the reason that when fastening the end of the strip to the end of the crate the perforation in the strip through which the nail 85 must pass is visible to the operator when the nail is placed in position with its point in the perforation preparatory to being driven into the end of the crate. Also, as before pointed out, only one nail is now used where formerly two were employed.

85 Although I have shown and described the nail as being driven upwardly through the perforation in the strip and into the end of the crate this may be reversed, in which case 90 the notch 14 would be above the kerf 13 and the nail would be driven downwardly. I prefer the method which I have shown, however, as the upwardly driven nail better resists any loosening which might be caused 95 by shocks and jars upon the strips at such times as the crate is being filled with bottles.

I claim:

100 A bottle crate having end walls each with a recess in its inner side and a notch communicating with said recess, a flat metal strip constituting a longitudinal partition member, said strip having each end let into 105

the recess in the corresponding end wall and being provided with a perforation in that portion within the recess but exposed by the notch, and a single securing nail driven 5 diagonally into the end wall substantially in line with the base of the notch, said nail passing through the perforation in the strip

and having its head contained within the notch and bearing upon that face of the strip which is exposed by the notch.

10

In testimony I have signed my name to this specification.

AMOS L. FOREMAN.
